UNITED STATES PATENT OFFICE

111,041

DESIGN FOR AN AIRCRAFT

Alexander P. de Seversky, Asharoken Beach,
Northport, N. Y., assignor to Seversky Aircraft
Corporation, Farmingdale, N. Y., a corporation
of Delaware

Application November 9, 1937, Serial No. 72,717

Term of patent 14 years

To all whom it may concern:

Be it known that I, Alexander P. de Seversky, a citizen of the United States, residing at Asharoken Beach, Northport, Suffolk County, State of New York, have invented a new, original, and ornamental Design for an Aircraft, of which the following is a specification, reference being had to the accompanying drawings, forming a part thereof. In these drawings,

Fig. 1 is a front elevational view of an aircraft showing my new design.

Fig. 2 is a side elevation thereof;

Fig. 3 is a top plan view thereof, and

Fig. 4 is a perspective thereof.

I claim:

The ornamental design for an aircraft, substantially as shown.

ALEXANDER P. DE SEVERSKY.
